A. C. WHEELOCK

ADJUSTABLE PIVOT MOUNTING FOR BED SUPPORTING PANELS

Filed Jan. 5, 1925

UNITED STATES PATENT OFFICE.

ARTHUR C. WHEELOCK, OF OAKLAND, CALIFORNIA.

ADJUSTABLE PIVOT MOUNTING FOR BED-SUPPORTING PANELS.

Application filed January 5, 1925. Serial No. 742.

My invention relates to a vertically adjustable floor pivot mounting for a panel or door arranged to carry a bed in up-ended position for movement through a wall-opening engaged by the panel, adjustment of the panel after installation being often necessary due to the settling of the building, sagging of the panel, clearance for rugs, etc.

An object of the invention is to provide an adjustable pivot mounting of the character described which will have permanently combined therewith complete, self-contained means operable without disturbing the panel or parts supported thereby, for effecting the adjustment thereof and maintaining the same in adjusted position.

Another object of the invention is to provide means of the character described, having adjustment maintaining means which in its normal operative position will lie inconspicuously disposed in the floor, and must be temporarily displaced from such position before readjustment of the mounting may be effected.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a vertical sectional view taken through the pivot mounting and associated portions of the floor and bed-supporting panel.

Figure 2 is a plan view of the portion of the device arranged to be directly associated with the floor.

Figure 3 is a sectional plan of a bed installation provided with the device of my invention.

Figures 4 and 5 are views similar to Figures 1 and 2, illustrating a modified form of the invention.

As illustrated in the drawings the pivot mounting 6 of my invention is particularly adapted for use in supporting upon a floor 7, a wall section, door, or panel 8, or similar member, on which a foldable bed 9 is adapted to be carried in up-ended position for move-

ment through an opening of a wall 10, such movement of the bed serving to transfer it from one room to another, or, as here shown, from a room 12 to a closet 13, or vice versa. 60

Referring now particularly to Figures 1 and 2, the device comprises a base member 14 having a plate portion 16 and a depending hollow boss 17. The plate 16 is arranged to be positioned, particularly when installation 65 is being made in a building under construction, on the sub-flooring or sheathing 18 upon which the usual layer 19 of hardwood is laid. The plate is preferably of the same thickness as the layer 19 so that the top surfaces of the 70 plate and floor will be flush.

The boss 17 of the base is provided adjacent the bottom with a threaded portion 21 in which is arranged to engage the threaded end 22 of one of the cooperating pivot 75 members 23 and 24 of the device. The pivot members are of a semi ball and socket type, and in the present embodiment the member 23 which contains the socket is arranged to be associated with the base and is thus 80 formed with the threads 22. The pivot member 24 contains the pivot stud 25 and is attached to the panel adjacent the lower edge thereof by means of a bracket 27 preferably formed integral with the stud. 85

It will now be clear that rotation of the socket member 23 will vary its position vertically, thereby causing a corresponding adjustment of the panel in the wall opening. Means are therefore provided for rotating 90 the member 23 and then locking it against rotation after the desired vertical adjustment has been secured, said means as hereinbefore pointed out being self contained, complete, and so designed that in normal operative position it will lie inconspicuously disposed in the floor, preferably practically entirely below the surface thereof. In accordance with the foregoing, the base 14 is formed with a depression 28 which, as here 100 shown, is arranged in the plate 16 and extends longitudinally thereof. Normally lying within the depression and being substantially of the same shape as the depression is a lever 29 having an end 31 arranged to engage the member 23. The member 23 is preferably formed with a polygonal exterior and the portion of the lever engaging same is correspondingly formed. In this manner with the lever seated in the depression and 105 engaging the member 23, the latter will be positively held against rotation and verti-

cal displacement. However, should conditions, such as the sagging of the panel, make necessary, a variation or adjustment of the position of the panel in its opening, the lever 5 may be raised vertically from the depression to operate above the top plane of the floor and so be used to rotate the member 23. Withdrawal of the lever from the depression by the operator is facilitated by the provision of recesses 32 which are disposed at the sides of the depression and permit the operator to grip the lever while it reposes in the depression. After the latter has been rotated sufficiently to bring the member 23 to 15 the desired height, the lever is allowed to again seat in the depression with the end 31 engaging the member 23 to thus positively maintain the panel in the new adjusted position. It will be noted that disengagement 20 of the lever from the member 23 while the former is seated in the depression, is prevented by the more or less snug fit between the adjacent side and rear edges of the lever and depression.

25 As will be clear by reference to Figure 1, the threaded and polygonal portions of the member 23, define the full length of said member, and since the latter is comparatively long, a wide range of vertical adjustment of the panel is afforded. If desired, a screw 30 may be used for securing the lever to the plate, so that surreptitious removal of the lever will not be so apt to occur.

30 In Figures 4 and 5, is shown a slightly modified form of the invention. In this embodiment, the handle portion of the lever is omitted, and as a result, a member 33 resembling a nut is seen in the place of the lever. The function of the member 33 is similar to that of the lever, with exception that in order to rotate the socket member 23 a 35 separate wrench or other tool (not shown) is required, the latter being arranged to be applied either to member 33 or directly to the socket member.

40 I claim:—

1. In an adjustable pivot mounting for a bed supporting panel, a base member embedded in a floor, and provided with a depression, a pivot socket carried by said member 50 and arranged to be vertically adjusted upon rotation therein, and means displaceably held seated in said depression arranged in normal position to hold said socket against rotation and arranged in displaced position 55 to be released from said member for rotation with said socket.

2. In an adjustable pivot mounting for a bed supporting panel, cooperating relatively fixed and vertically adjustable pivot members respectively secured to said panel and a floor, said adjustable member being mounted for rotation to effect adjustment thereof, and a displaceably positioned lever for rotating said member normally held seated in a like shaped depression in said floor to hold said member against rotation.

3. In an adjustable pivot mounting for a bed supporting panel, a base member embedded in a floor, and provided with an elongated depression and a threaded hole, a threaded member engaging in said hole and provided at the top with a pivot socket and a polygonal exterior, a pivot stud engaging in said socket and fixed to said panel, and a wrench normally seated in said base-member depression and engaging said exterior of the threaded member to prevent rotation of the latter and arranged to be raised from said depression in order that the wrench may 70 be used to rotate said threaded member.

4. In a supporting pivot structure for a bed supporting panel, a vertically adjustable pivot member mounted on a floor and arranged for rotation to effect adjustment 85 thereof, said floor being provided with a depression extending from adjacent said member, and a wrench normally held in said depression and engaging the pivot member to prevent rotation thereof and arranged to be 90 raised from said depression in order that the wrench may be used to rotate the member.

95 In testimony whereof, I have hereunto set my hand at Oakland, California, this 28th day of November, 1924.

ARTHUR C. WHEELOCK.
